ILLUMINATED SIGN

Filed Jan. 12, 1928

INVENTOR
BY
Aaron L. Applebaum
ATTORNEY

UNITED STATES PATENT OFFICE

BENJAMIN EMIS, OF NEW YORK, N. Y., ASSIGNOR OF ONE-HALF TO IRVING L. SCHON-BRUN, OF BROOKLYN, NEW YORK

ILLUMINATED SIGN

Application filed January 12, 1928. Serial No. 246,360.

The object of my invention is to provide an illuminated sign in which the advertising matter or display is visible from the front or back.

One of the objects of my invention is to provide an illuminated sign adapted to be positioned or suspended on or from an object and in which natural or artificial light may be reflected in at least two directions or toward the front and back through a casing having advertising or display matter for exhibition.

More specifically my invention relates to an illuminated sign consisting of a casing having front and rear reflecting mirrors positioned on a plain or ground glass surface, said mirrors having advertising or display matter thereon, the top of said casing being provided with a window whereby natural or artificial light may be projected for reflection against the said mirrors to illuminate the matter to be displayed.

My invention relates to improvements in illuminated signs of the type granted to Roy Austin, October 11, 1927, No. 1,644,663.

To enable others skilled in the art to more fully comprehend the underlying features of my invention, its advantages and useful results obtained, reference is had to the accompanying drawing showing a preferred embodiment in which

Fig. 1 is a perspective view showing my invention.

Fig. 2 is a cross sectional view.

Fig. 3 is a partial sectional view of the reflecting mirror and advertising or display matter thereon.

Fig. 4 is a sectional view through the casing wall window and reflecting mirror.

Referring now to the drawings wherein like reference characters designate corresponding parts throughout the several views, 5, 6 designate the ends of a trough-shaped, elongated casing, preferably constructed of light metal capable of being stamped, such as galvanized iron, tin, aluminum, etc. The ends 5, 6 are substantially V-shaped, the sides being provided with flanges 7 and the top edges with an inwardly directed flange 8.

The ends of the casing are also connected

by a narrow bottom wall 9 having angularly disposed side flanges 10, 11. A pair of substantially L-shaped channel bars 12, 13 are permanently connected to the side flanges 7, thus producing a casing open at its front, 55 rear and top but closed at its ends.

Connected to the bottom wall 9 is a pair of U-shaped spring clamps or clips 14 and similar spring clamps or clips 15 are provided on the faces of the ends to retain the front and rear windows and reflecting mirrors, further to be described. The L-shaped channel bars 12, 13 and the top flanges 8 of the ends form a guide and support for a top window 16. 60

Referring specifically to Figs. 3 and 4 of the drawing, the front and rear sides of the casing are provided with pellucid panes 17 of any desirable color and which may be of ground glass or any translucent material through which the light may pass. Each pane is silvered as at 19 and coated with an opaque coating 20. The silvered and coated surface is blocked out to produce the letters, indicia or advertising matter 21 to be displayed or exhibited. After coating with opaque paint, the silvered surface of the letter proper may be removed by means of an acid so that the letter is transparent. The opaque coating is on the inside but does not of course 70 cover the letters so that there is a reflection within the casing and from one panel to the other and through both the front and rear of the sign. The mirror surface of each plate being disposed at an angle toward the other reflects the light both toward the front and back and through the outer window 17 and the opaque coating permits the light to pass through the blocked out letters or advertising matter only. 75

Where the casing is employed for outdoor purposes, such as on store-fronts, motor vehicles and the like, in order to prevent dust, dirt or rain from entering and adhering to the mirrors, the casing is provided with a plain top window 16 which may be of glass or other translucent material, but where the casing is employed indoors, the top window may be dispensed with. Any suitable means may be employed to position or suspend the casing 95 100

from a support as by chains, hooks or pivots preferably attached to the ends (not shown).

From the above construction, it will be seen that the casing is designed to permit the natural or artificial light from the top to enter and be reflected by the interior mirrors and through the front and rear windows thus exhibiting or displaying the advertising matter. Various color effects may be produced by employing different windows at the back of the mirrors. While I have referred to the use of glass mirrors, it will also be understood that any mirrored surface such as highly polished metal may be employed for the same purpose.

While I have shown and described my invention with some degree of particularity, it will be understood that various changes in the details, design and construction may be resorted to. I therefore do not wish to be limited and restricted to the exact and specific embodiment shown but reserve the right to make such changes and modifications as may fairly fall within the scope of the subject matter being claimed.

Having shown and described my invention, what I claim as new and desire to secure by Letters Patent is:

A sign comprising a substantially triangular casing and having reflective panes in two of its sides, means for rigidly mounting said panes at an angle of substantially 45 degrees to each other, said panes having an opaque reflective coating on their inner surfaces, and having portions of said coating removed so as to form signs whereby light reflected from each reflective surface passes through only the translucent portions of the other pane, and a light transmitting pane between and above said panes for admitting exterior light to said panes.

In testimony whereof I affix my signature.
BENJAMIN EMIS.
